UNITED STATES PATENT OFFICE

MAURICE ALLAND, OF ATLANTIC CITY, NEW JERSEY

ELASTIC-PROPELLED TOY VEHICLE

Application filed November 30, 1928. Serial No. 322,805.

The object of this invention is to provide improvements in toy vehicles, and particularly in that type which is automatically propelled along a surface upon being released 5 after winding certain elastic means by manually propelling it in reverse direction upon said surface.

Another object has been to construct a toy of this character in which the movement of 10 the toy when released creates a sound which is similar to and represents the familiar sound given off by an automobile when the muffler is cut out.

A further object is to so construct the toy 15 that the propulsion of it when released is caused by the unwinding of a rubber band, or similar element, which at one end is readily attached to or disconnected from a relatively fixed portion of the article, while its opposite 20 end portion is secured to a hook or other suitable means carried by the driving axle; and from which said band or the like is readily disengageable when desired, but which hook forms a normally permanent connection 25 between the band and the axle to all intents and purposes.

Still another object is to provide the driving axle with collars upon opposite sides of 30 the hook to prevent the elastic or the like from entering and entangling with the bearings of said axle, at least one of such collars comprising a toothed gear or ratchet which is engaged by a resilient member secured at 35 its opposite end to the body of the vehicle, so that vibrations set up in said member through rotation of said toothed collar are communicated to said body and thereby magnified to create an easily audible sound.

With these and other objects in mind the 40 present invention comprises further details of construction and operation which are fully brought out in the following description when read in conjunction with the accompanying drawings in which Fig. 1 is a side 45 elevation of a toy vehicle comprising one embodiment of the invention; Fig. 2 is a longitudinal vertical section of the same; and Fig. 3 is a bottom plan view of the same.

Referring to the drawings, a vehicle 1 50 is illustrated as representing any well-known

type of automobile, but may instead represent any other form of vehicle desired. Being a toy, it is preferably made in the form of a shell, substantially as shown in Figs. 2 and 3, said shell comprising a top wall 2 which 55 has an integral offset 3, representing the bust of a driver, a forward wall 4 and oppositely positioned side walls 5. Rotatably mounted upon the outer side of each of the side walls and the forward portion thereof is a wheel 6, 60 surrounded by a tire 7, in order to prevent these forward wheels from skidding laterally as the vehicle is propelled rapidly forward over a given surface. Extending forwardly from the lower portion of the forward wall 4 65 is a lug 8, representing the well-known connection provided for attachment of a crank, which in a genuine automobile serves the purpose of manually starting the engine when such is necessary. This lug may comprise the 70 head of a screw or pin, the opposite end of which extends inwardly through the front wall and provides a hook 9 adapted to normally and detachably receive one looped end 75 portion of a rubber band or other suitable form of elastic 10, the opposite end of which elastic detachably engages a hook 11, which is secured to and extends longitudinally of the rear driving shaft 12 of the vehicle.

Said driving shaft extends rotatably 80 through the side walls 5 of the vehicle and upon its outer ends supports driving wheels 13, provided with tires 14 for frictionally engaging a given surface and insuring the tractive effort of the driving wheels with respect to said surface.

It has been found through extensive experiments that as the driving wheels are rotated in a reverse direction in any suitable manner, as for instance by manually gripping the vehicle and moving it rearwardly with the driving wheel tires in contact with a given surface, the elastic 10 in winding upon the shaft 12 tends to wind toward one end or the other 95 of said shaft and would enter the journal supports of the same were it not for a pair of collars carried by said shaft.

In the present embodiment of the invention these collars 15 and 16 are secured to the 100 shaft between the hook 11 and the vehicle

walls 5, one of said collars being a mere flange or washer, while the other of said collars is notched to provide the equivalent of a ratchet or gear, having peripheral teeth which are yieldingly engaged by the free end portion of a resilient member 17, the opposite transversely enlarged end portion 18 of which is normally secured rigidly to the upper wall 2 or any suitable portion of the vehicle body by means of a rivet, bolt, screw, or any other desired form of connection 19.

It has been found that with relatively light toys of this general nature in equipping them with propelling mechanisms which tend to cause a sudden and rapid rotation of their driving wheels when released, it is necessary to weight them in such manner that a more positive cooperation between the driving wheels and the supporting surface is insured. In the present instance this has been accomplished by means of a disc 20, preferably of lead and secured in any suitable manner to the rear portion of the inner surface of the upper wall 2 of the vehicle. As will be seen from Figs. 2 and 3, the additional weight contributed by this disc 20 is substantially directly above the axis of the driving wheels 13.

In the operation of the device, as previously referred to, the vehicle body is manually gripped and placed upon and with the driving wheel tires 14 in contact with a given surface, whereupon the vehicle is moved in a direction which is the opposite to that which it is intended to take when released and subsequently moving under its own power. As the vehicle is thus moved manually, the elastic 10 winds upon the driving shaft 12 as far as may be desired, or as far as may be safe within the limit of elasticity of such elastic, after which the vehicle body can be released and the tension of such elastic will operate to reversely rotate said driving shaft and propel the vehicle along the surface upon which it rests.

As the vehicle is propelled rapidly forwardly under the power of the contracting elastic 10, the rapid frictional engagement of the resilient member 17 with the notched or toothed collar 16 creates an intermittent sound which is conveyed to the upper wall 2 of the vehicle body which acts as a sounding board, the hollow interior of the body acting as a resonance chamber, and the sound escaping therefrom both from beneath the end and side walls 4 and 5 and also from the upper surface of the top wall 2. By modifying the shape, size and resiliency of the member 17, the number and shape of the notches on the collar 16, the method of attachment of the member 17 to the body wall 2, and by varying the material of the vehicle walls themselves, a wide range of audible sounds may be produced, including among others the well-

known sound created by an automobile when running with the muffler cut out.

It is also to be noted that by extending the hook 11 parallel with the shaft 12, when the elastic 10 has become fully unwound from said shaft and the momentum of the vehicle starts to wind said elastic reversely, there is no danger of the elastic jumping from said hook as was found to be the case when a hook was employed having a direction other than parallel with said shaft. It is also to be understood that the fixed end portion of the elastic may be attached to the body of the vehicle in any suitable manner whatever in addition to the hook 9 as shown.

Furthermore, it has been found that when operating the device upon an inclined surface, it will propel itself in the manner described either upwardly or downwardly of such surface, but whether up or down, when the power of the elastic is spent, said elastic serves in effect as a brake, and prevents the device from moving downwardly under the force of gravity, until manually so moved or raised freely from said surface.

Having thus described my invention, what I claim and desire to protect by Letters Patent of the United States is:—

A toy vehicle, comprising a hollow shell comprising top, side, and end walls and open at the bottom, a driving shaft journaled through said side walls, a weight secured to said vehicle substantially above said shaft, wheels fixed to said shaft, a hook carried by the central portion of said shaft and directly in parallelism therewith, a lug carried by said shell, an elastic extending between said lug and said hook, a toothed collar secured to said shaft between said hook and one of said journals, and a resilient member secured at one end to said vehicle and having its free end in engagement with the teeth of said collar to create a vibratory sound as the shaft rotates under the impulse of said elastic when released after previous rotation of said shaft has caused said elastic to be wound thereupon.

In testimony whereof I have affixed my signature.

MAURICE ALLAND.
